UNITED STATES PATENT OFFICE

EDWARD SCHULTZ, OF CHICAGO, ILLINOIS, ASSIGNEE TO WILLIAM H. JENKINS, OF CHICAGO, ILLINOIS.

DESIGN FOR A VENDING-MACHINE CASING.

Application filed October 29, 1925. Serial No. 15,286. Term of patent 3½ years.

To all whom it may concern:

Be it known that I, EDWARD SCHULTZ, a citizen of the United States, residing at Chicago, in the county of Cook and State of Illinois, have invented a certain new, original, and ornamental Design for Vending-Machine Casings, of which the following is a specification, reference being had to the accompanying drawing, forming part hereof.

The figure is a perspective view of a vending machine casing showing my new design.

I claim:

The ornamental design for a vending machine casing, as shown.

EDWARD SCHULTZ.

Certificate of Correction.

It is hereby certified that the name of the assignee in Design Letters Patent No. 69,057, granted December 15, 1925, upon the application of Edward Schultz, of Chicago, Illinois, for a "Design for a Vending-Machine Casing," was erroneously written and printed "William H. Jenkins," whereas said name should have been written and printed as William N. Jenkins, as shown by the records of assignments in this office; and that the said Letters Patent should be read with this correction therein that the same may conform to the record of the case in the Patent Office.

Signed and sealed this 19th day of January, A. D. 1926.
